UNITED STATES PATENT OFFICE.

ISAAC BICKHART, OF HARLAN, INDIANA.

IMPROVED BOOT AND SHOE BLACKING APPARATUS.

Specification forming part of Letters Patent No. 37,487, dated January 27, 1863.

To all whom it may concern:

Be it known that I, ISAAC BICKHART, of Harlan, in the county of Allen and State of Indiana, have invented a new and Improved Machine for Cleaning and Blackening or Polishing Boots and Shoes; and I do hereby declare that the following is a full, clear, and exact description of the same, reference being had to the accompanying drawings, making a part of this specification, in which—

Figure 1 is a transverse vertical section of my invention, taken in the line $x x$, Fig. 2; Fig. 2, a plan or top view of the same; Fig. 3, a detached view of a portion of the same, showing the adjustment of the brush-wheels; Fig. 4, a detached side view of a hand-brush pertaining to the same.

Similar letters of reference indicate corresponding parts in the several figures.

This invention consists in the employment or use of one or more revolving adjustable brush-wheels, in connection with one or more yielding foot-stands, arranged in such a manner that boots and shoes may be expeditiously cleaned and blackened while on the feet of the wearer.

To enable those skilled in the art to fully understand and construct my invention, I will proceed to describe it.

A represents the base of the machine, which has two uprights, $a a$, attached to it, in which the journals of a horizontal shaft, B, are fitted and allowed to rotate freely. This shaft B is rotated from a driving-shaft, C, through the medium of gears $b c$, and the shaft C may be rotated manually by means of a crank, D. (See Figs. 2 and 3.) On the shaft B there are placed two brush-wheels, E E, each of which is formed of two parts, $d d$, the parts D being firmly keyed to the shaft B, and the parts d fitted loosely upon it so that they may slide freely thereon. The two parts $d d$, which compose each brush-wheel E, are of curved-cyma form at their inner sides, as shown clearly in Figs. 2 and 3, and the bristles e are inserted in these curved sides of the parts $d d$, and each of said parts terminates in a cylindrical projection or hub, f, which are slotted longitudinally so as to form a clutch and cause said parts to be connected so that the part d , which is keyed to the shaft B, will

turn the part d' , which is fitted loosely thereon, and the slots in the hubs f are made sufficiently deep to admit of the parts $d d'$ being connected under a considerable play or movement of the part d' . This will be fully understood by referring to Fig. 3. The parts d' of the brush-wheels have a spiral spring, C, bearing against them, and this spring is placed on the shaft B between the parts d' , as shown clearly in Fig. 2. The spring C has a tendency to keep the parts $d' d'$ of both brush-wheels in close contact with the parts $d d$.

D D represent two foot-stands, which are simply two pieces of boards placed horizontally on the upper ends of springs E, which are of spiral form and attached at their lower ends to the base A. The springs E are of such a height that the foot-stands D D will be about in line with the lower edge of shaft B. Each foot-stand D is supported by two springs, E.

The operation is as follows: The person places the machine on the floor in front of him, and, being seated on a chair, places his foot on one of the foot-stands E, and presses it downward and forward so that the upper of the boot or shoe will be underneath the brush-wheel, the part d' thereof yielding so that the brush-wheel will conform to the size of the boot or shoe. The shaft C is rotated by an attendant, and the upper part of the boot or shoe will be cleaned or freed from dust and dirt. The person then withdraws his foot from the foot-stand, and places it on the top of the brush-wheel, which then cleans the heel and back part of the boot or shoe. These two positions of the boot are shown in red outline in Fig. 1. The person then applies blacking to the boot or shoe by means of a brush, F, the blacking-box G being secured on the base A, at the outer side of one of the uprights a . When the boot or shoe is blacked it is operated upon and polished by the other brush-wheel, E, the boot or shoe being applied to the brush-wheel in the same manner as previously described for clearing off the dust and dirt. Two brush-wheels are desirable in order that the blacking brush-wheel may always be kept clean. One brush-wheel to answer both purposes—to wit, clearing off the dirt and polishing—although it might

be used, would not answer a good practical purpose.

Having thus described my invention, what I claim as new, and desire to secure by Letters Patent, is—

The revolving brush-wheels E E, one or more, constructed substantially as shown, in

combination with the yielding foot-stands D D, arranged substantially as and for the purpose herein set forth.

ISAAC BICKHART.
